Robert C. Fischer
Inventor:

UNITED STATES PATENT OFFICE.

ALBERT C. FISCHER, OF CHICAGO, ILLINOIS.

CROWNING STRIP FOR EXPANSION JOINTS.

Application filed October 19, 1925. Serial No. 63,360.

This is in part a continuing application of my application Serial No. 569,247, filed June 19, 1922, container form for expansion joint and method of installing same.

5 Crownings strips heretofore have been made of metal for the purpose of holding plates in position, or for the purpose of acting as a covering to prevent ingress of foreign material into openings thus protected 10 which are later to be filled, and are therefore, a removable part of the contrivance.

My invention relates primarily to reinforcing a moulding strip, which may be of any rigid material, such as, wood and preformed 15 expansion joint, heavy flax strips, or flexible cellular joints adapted to strips, functioning as a moulding board or spacing board, which may be either removed from the crevice or may be allowed to remain permanently 20 in the crevice, in which case the crowning strip would be removed. The function of the crowning strip being primarily to reinforce the moulding strip or expansion joint at the crown, and keep it in a 25 straight line and thus aid as a supporting means until the concrete is laid about the expansion joint or moulding strip, holding it in a straight line, thus preventing it from forming a wavy condition, and permitting 30 the installation of an expansion joint in a straight line, rather than a wavy line which might otherwise take place.

Where this strip is utilized in this manner it would not be necessary to provide an 35 envelope. A moulding strip may be out of any material, and when out of material which would be adapted as an expansion joint, especially in hot weather, such strips are very often wavy, and by utilizing the 40 cap, as described, over the crown of the moulding strip it not only protects the edges of the moulding strip but also enables the moulding strip to be reinforced at the crown, thus straightening that part of the joint 45 coming to the surface of the concrete, and also protecting the joint or moulding strip from injury. This material may be formed out of wood, metal, band-iron, heavy saturated paper, or any suitable material. It 50 may be furnished at the plant or may be shipped to the job with the moulding strips, or when formed in different manner may be inserted in the crown.

55 My invention may best be understood by referring to Figure 1, which illustrates a crowning strip, as described, a represent-

ing the top portion of the crowning strip and b, b the downwardly extending portions of the crowning strip.

Figure 2 illustrates this crowning strip 60 formed out of metal with a as the top portion of the crowning strip and b, b as the depending portions of the crowning strip.

Figure 3 describes a crowning strip in which a, a is the top portion, b, b the depending side portions and b, b a depending center portion.

Figure 4 illustrates these crowning strips in position when used in combination with the moulding strip or expansion strip in 70 right form.

It can be readily understood that in heat a moulding strip might readily warp, and in being thrown around, as occurs on highways, it can readily be deformed. The application of the metal crowning strip would prevent this deformation, at least as far as the crown is concerned, and enable one to make a straight line installation by pouring the concrete d, d on either side of the 75 moulding strip c and it is then only a matter of a few moments, after the setting of the concrete, to remove the crowning cap a with the depending flange b, b, thus leaving the moulding strip snugly in position between the concrete slabs.

Figure 5 illustrates a moulding strip, rigid in form, adapted to be left in position between the concrete slabs d, d and having its crown reinforced with a crowning strip 90 a, a with a depending penetration groove b by soaping the underside of this crowning strip when forcing the same into the crown, it can readily be removed after installation, but a suitable device can be inserted in the 95 groove b pressing the crown of the moulding strip apart, leaving it in condition as shown in Figure 6.

In Figure 6 the crowning strip has been removed after depressing the moulding strip 100 c and allowing same to remain between the concrete slabs d, d. This depression has been caused by a suitable device inserted in the groove b pressing the crown of the moulding strip apart.

105 It can readily be understood that the thickness of the material used as a crowning strip may be modified to adapt the crowning strip for the various purposes described, and where it is the purpose to employ as a moulding strip a rigid wood filler and heavy type 110 would have to be employed, as in Figure 1,

while if the moulding strip was prepared from bituminous compressible material, which would be permitted to remain in the concrete, a crowning strip such as shown in Figure 2, would be utilized for the purpose of straightening the material and holding it in shape while the concrete is being poured. A still lighter material may be employed when utilized as in Figure 3.

These strips may be formed by any suitable machinery adapted for that purpose. The installations are made by placing the crowning strip on the moulding strip or separating strip, and then staking the separating strip in position, either against a suitable backing board or by driving the stakes directly against the sides of the moulding or separating strip.

I claim:—

1. In combination, a preformed expansion joint, comprising a strip of compressible ma-

terial, and a reinforcing crown fitting over the edge of the strip and having depending portions extending over the sides of the strip.

25

2. A crowning strip having flat upper portions and depending outer side portions, with a depending grooved center portion, the side walls thereof being placed in contacting relation.

30

3. A metal crown for the edge of a bituminous expansion joint, comprising a metal strip longitudinally folded upon itself to provide a downwardly depending center rib, and a flat top portion at right angles to said rib, said rib adapted to be imbedded in the material of the joint with the flat top portion overlying the edge of the joint substantially as/and for the purpose described.

35

Signed at Chicago, Illinois, this 13 day of October 1925.

ALBERT C. FISCHER.
